US0D1112060S

(12) **United States Design Patent** (10) **Patent No.:** **US D1,112,060 S**
(45) **Date of Patent:** **** Feb. 10, 2026**

(54) **CASE**

(71) Applicant: **Apple Inc.**, Cupertino, CA (US)

(72) Inventors: **Kjell Ferdinand Ekman**, Los Angeles, CA (US); **Jeffrey Scott Croyle**, San Francisco, CA (US); **Christina J. Smiechowski**, West Hollywood, CA (US); **Duy P. Le**, Venice, CA (US); **Dillon Q. Johnson**, Los Angeles, CA (US); **Patricio Romano**, Camarillo, CA (US); **Christopher Kuh**, San Francisco, CA (US); **Guillaume Raoult**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/938,416**

(22) Filed: **Apr. 19, 2024**

(51) LOC (15) Cl. **13-02**

(52) U.S. Cl.

USPC **D13/108**

(58) **Field of Classification Search**

(57) **CLAIM**

The ornamental design for a case as shown and described.

DESCRIPTION

FIG. 1 is a top front isometric view of a case showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a cross-sectional view thereof taken along line 9 of FIG. 7.

The dashed broken lines in the figures show portions of the case that form no part of the claimed design.

The cross-hatching in FIG. 9 forms no part of the claimed design.

1 Claim, 9 Drawing Sheets
